UNITED STATES PATENT OFFICE.

JACOB SCHWARZKOPF, OF TOLEDO, OHIO.

AWNNG-CORD GUIDE FOR WINDOW SCREENS.

Application filed December 22, 1927. Serial No. 241,866.

This invention relates generally to attachments for window screens and aims to provide means whereby the cords of awnings may be freely passed through the frame of a window screen so that the awning may be raised or lowered from within the building and without requiring the raising or the removal of the screen.

In carrying out the present invention, there is provided a highly novel, simple and inexpensive cord guide that may be applied to the upper or lower horizontal bar of a window screen and adjacent an opening therein so that the cord may be passed thereover and through the opening with the result that the same may be pulled from inside of the room.

In the event the cord is passed through the upper frame bar one of the guides is placed upon both the outer and inner sides of the frame, whereas in the event the cord is brought downwardly in front of the screen and passed through an opening in the lower frame bar it is only necessary to arrange one of the guides at the outer side of the bar and adjacent said opening.

In the drawing wherein like reference characters indicate corresponding parts throughout the several views:—

30 Figure 1 is a section and perspective fragmentarily of the upper end of a window screen through the horizontal frame bar of which is an opening through which an awning cord is arranged, said cord being guided at the inner and outer sides of the frame bar by reason of a pair of the cord guides constructed in accordance with the present invention.

Figure 2 is a similar view of the lower end of a screen through the frame bar of which is an opening through which the awning cord is to be arranged after the same has been drawn downwardly at the outside of the screen, said cord being guided prior to engagement through the opening through the provision of one of my improved guides, and,

Figure 3 is a front elevation of one of the guides per se.

50 Now having particular reference to the drawing there is disclosed in Figures 1 and 2 a conventional window screen A. In Figure 1 the upper horizontal frame bar is designated *a* while in Figure 2 the lower horizontal frame bar is designated *a'*. In the event it is desired to pass the awning cord B

through the uppermost bar *a* two of the guides constructed in accordance with the present invention are used, these guides being designated generally by the reference character 60

5. Before applying these guides it is necessary to drill a hole through the frame bar, either the upper or lower one as clearly indicated by the dotted lines in Figure 2. When arranging the cord through the upper frame bar two of the guides 5—5 are provided, the same being arranged at opposite sides of the frame bar and at the ends of the opening as disclosed. However, when it is desired to extend the cord B downwardly at 70 the outer side of the screen and thence pass the same through a previously drilled opening through the lower frame bar *a'* only one of the guides is necessary this guide being arranged at the outer side of the frame 75 bar directly at the end of the opening is disclosed.

The particular guide consists of a metallic plate 6 of predetermined length and relatively narrow width. At the longitudinal edges 80 of the plate the same is formed with outwardly extending ears 7—7 of gradually tapering formation the wider ends thereof terminating in spaced relation with one end of the plate. The opposite ends of the plate 85 are formed with openings 8—8 in order to permit the same to be screwed, tacked, nailed, or otherwise rigidly secured to the desired frame bar of the window screen. Arranged between the wide ends of the ears 90 7—7 is a pin 9 upon which is loosely arranged a cord guide roller 10. Directly adjacent this roller and at a point substantially intermediate the ends of the plate, said plate is formed with an enlarged opening 11 through which the cord B is to be extended, it being obvious that the plate is to be so arranged with respect to a chosen one of the frame bars of the screen so as to register with the adjacent end of the previously drilled hole within the frame bar. 95

When the cord B is passed through an opening in the upper frame bar of the screen the guides 5—5 are so arranged that the cord B will be passed over the roller whereas when the cord is to be passed through an opening in the lower frame bar of the screen as in Figure 2, the guide is so arranged that the cord will pass beneath the roller in each instance it being obvious that the cord will 100 be properly guided through the opening in the screen frame so that there will be no lia- 110

bility of the cord becoming frayed by rubbing against the ends of the opening.

In view of the foregoing description when considered in conjunction with the accompanying drawings, it will be apparent that I have provided a highly novel, simple and efficient awning cord guide for window screens.

Having thus described my invention, 10 what I claim as new is:—

In an awning cord guide for window screens wherein the cord is to be arranged through an opening in the screen frame, a

plate adapted for attachment to the frame and being formed with an opening therein 15 for registry with an opening in the screen frame, when the plate is secured to said screen frame, said plate having its longitudinal edge portions bent laterally to provide oppos'd spaced flanges, a roller journaled between the said flanges and in offset position with respect to the opening in the plate, and over which the awning cord may be trained.

In testimony whereof I affix my signature.

JACOB SCHWARZKOPF.
